US00D682418S

(12) **United States Design Patent**
Krepel et al.

(10) **Patent No.:** **US D682,418 S**
(45) **Date of Patent:** **** May 14, 2013**

(54) **RESPIRATOR BELT HAVING ATTACHMENT SLOT**

(75) Inventors: **Kenneth J. Krepel**, North St. Paul, MN (US); **Nathan A. Abel**, Minneapolis, MN (US); **Jia Hu**, Mounts View, MN (US)

(73) Assignee: **3M Innovative Properties Company**, St. Paul, MN (US)

(**) Term: **14 Years**

(21) Appl. No.: **29/413,385**

(22) Filed: **Feb. 15, 2012**

(51) **LOC (9) Cl.** **29-02**

(52) **U.S. Cl.**

USPC **D24/110**

(58) **Field of Classification Search** D24/110, D24/127; D6/553; D8/366, 371, 373; 52/633; 211/73; 128/202.13, 207.17, 876; 248/450

See application file for complete search history.

(57) **CLAIM**

The ornamental design for a respirator belt having attachment slot, as shown and described.

DESCRIPTION

FIG. 1 is a front perspective view showing the new design for a respirator belt having attachment slot;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken line showing of portions of the article is included for the purpose of illustrating environmental structure and forms no part of the claimed design.

1 Claim, 2 Drawing Sheets
